UNITED STATES PATENT OFFICE.

GEORGE HOHENSTEIN, OF RINGWOOD, ILLINOIS.

CORN-HUSKING ROLLS.

1,361,463.

Specification of Letters Patent. Patented Dec. 7, 1920.

Application filed January 14, 1918. Serial No. 211,794.

To all whom it may concern:

Be it known that I, GEORGE HOHENSTEIN, a citizen of the United States, residing at Ringwood, in the county of McHenry, State 5 of Illinois, have invented certain new and useful Improvements in Corn-Husking Rolls; and I do hereby declare the following to be a full, clear, and exact description of the invention, such as will enable others 10 skilled in the art to which it appertains to make and use the same.

This invention relates to corn husking machines, and has particular reference to the construction of the husking rolls.

15 The object of the invention is to provide an improved form of husking mechanism by a more efficient arrangement of the husking teeth or fingers with relation to the rolls, together with a practical mounting therefor. 20 By means of my improved construction, the teeth and their mountings may be manufactured at a minimum expense, and the teeth so inserted therein or secured thereto that they may be sharpened without removing the 25 mountings from the rolls. Provision is also made, in the assemblage of the rolls to prevent the breaking of the teeth when the driving gears of the rolls accidentally become disarranged so as to cause the teeth to rotate 30 in untimed relation.

With the above objects in view, and such others relating to the details of construction, as may hereinafter appear, my invention will now be fully set forth and described, 35 reference being had to the accompanying drawings.

In the drawings:—

Figure 1 is a fragmentary plan view of a pair of rolls, having the invention mounted 40 thereon,

Fig. 2 is a fragmentary perspective view of one of the rolls,

Fig. 3 is an enlarged perspective view of one of the mountings with its associated 45 teeth,

Fig. 4 is a transverse section through the rolls, and

Fig. 5 is an enlarged section through one of the tooth mountings.

50 Referring more particularly to the drawings, 1 and 2 represent the rolls of a corn husking machine which are mounted in contiguous parallel relation so as to close the bottom of an elongated hopper. The 55 rolls 1 and 2 may be constructed of wood, metal or a combination of these materials

in accordance with any particular or desired method. At regular intervals, the rolls 1 and 2 have cut into their peripheral surfaces the wide channels 4 and the narrow channels 60 or grooves 5, the wide channel 4 and the groove 5 coming into closely spaced relation for the purpose which will hereinafter appear, and, with relation to the juxtaposed rolls, a narrow groove of one roll appearing 65 opposite the wide channel 4 of the opposite roll.

The channels 4 provide seats for annular bands, each made in a plurality of sections 6, and preferably in two semi-circular 70 sections as shown, meeting end to end and held within each channel removably by fastening means such as the screws 7. The band as so constituted is as thick and as wide as the channel so that when in place its periphery complements that of the roll and, as seen in Fig. 1, each channel is wider than the opposite groove so that the band within it extends beyond both side walls of such groove. The band sections 6, in the form 80 illustrated, are provided with sockets having spiral bottoms growing gradually deeper in the direction of rotation of the rolls to their rear ends 10 which are abrupt and radial. Each tooth 8 has a curved bottom 85 resting on the bottom of the socket, a broad sharp cutting edge 12 undercut at its front end as at 13, and a receding back 14. The front end of the tooth is wholly beyond the periphery of the roll as seen in Fig. 5, its 90 rear end is wholly within the socket at the rear end 10 of the latter, and its body between these ends is both curved and tapered from front to rear. The angles 12 between the front ends and backs of the teeth are 95 sharpened so as to provide broad cutting edges which will take hold of the husks of the corn deposited in the hopper, and tear them from the ears. When the peripheries of the rolls 1 and 2 roll one against the 100 other, the outstanding parts of the teeth on one roll operate in the groove 5 of the opposing roll; and in gearing the rolls together, the teeth of the opposing rolls are so arranged that two contiguous teeth pass between the rolls at the same time, so that as the tops of the rolls move toward one another within the hopper, the cutting edges of these teeth will strike into the husks of the ears of corn simultaneously from opposite sides.

In the construction which has been de-

scribed, the teeth are so arranged that they will husk the corn thoroughly with a smaller percentage of shelling of the kernels than is possible with any of those husking rolls 5 which have been heretofore known to me. Furthermore, the manner of mounting of the teeth is such that they will possess a comparatively long life, and when they become dulled they can be filed with a minimum of 10 effort without being removed from the rolls. The grooves 5 in which the teeth operate prevent injury to the teeth when the rolls are spread so that the gear wheels slip over one another so as to untimely the operation of the 15 teeth.

As a matter of manufacture, the teeth are mounted upon semi-circular bands which may be supplied for the renewal of the teeth upon used rolls, and while the teeth are 20 shown in the present instance as inserted into the bands, they may be otherwise secured thereto or they may be formed as integral elements of the bands.

It is well known that heretofore husking rolls have been constructed with pointed teeth on one roll received in grooves in another roll, and in the operation of the husking machine the teeth, by reason of their pointed formation, penetrate the grains of 30 corn and cause the grains to be mutilated and pulled from the cob. These teeth when entering the grooves do not completely close the same on opposite sides of the teeth, and thus the space becomes crowded with 35 the cobs and husks, and the resultant pulling action of said husks will cause the grains to be shelled, as well as clogging the husks in the grooves of the rolls in the machine when operated.

40 In the present invention, the teeth are formed with broad cutting edges which completely close the grooves entered thereby, thus holding the ears out of said grooves and avoiding clogging by the husks and at 45 the same time preventing the teeth cutting through said husks and shelling the grain from said cob. The rolls hold back the ears,

and, by reason of the disposition of the teeth and the width thereof closing the grooves in said rolls, prevent the entrance of the ears, 50 husks, or grains therein while the teeth will be restricted to limit penetration into the husks in the operation of the husking machine.

It will therefore be obvious that I have 55 provided a very simple and efficient organization of parts for the husking rolls of corn husking machines.

What claim as my invention is:—

1. Corn husking mechanism comprising 60 two rolls rotated oppositely and in contact and each having relatively narrow annular grooves and relatively wide annular channels respectively opposite like channels and grooves in the other roll, a band in each 65 channel made up of a plurality of sections of a thickness and width to fill the channel and to extend beyond the edges of the groove in the opposite roll, means for securing said sections removably in place end to end, and 70 teeth on each section extending beyond its periphery and of a width to fill said groove.

2. Corn husking mechanism comprising 75 two rolls rotated oppositely and in contact and each having annular channels opposite 80 grooves in the other, semi-circular band sections removably secured in and filling each channel and having sockets whose bottoms grow deeper from front to rear in the direction of rotation and whose rear ends are 85 abrupt and radial, and a tooth fitted in each socket with its front end extending beyond the periphery of the roll and undercut, its cutting edge of the same width as the groove with which it coacts, and its back receding to its rear end where it is flush with the periphery of the roll.

In testimony whereof I affix my signature in the presence of two witnesses.

GEORGE HOHENSTEIN.
